UNITED STATES PATENT OFFICE.

ALFRED JASPER HENDERSON, OF DALLAS, TEXAS.

PUZZLE.

1,296,955.

Specification of Letters Patent. Patented Mar. 11, 1919.

Application filed September 18, 1918. Serial No. 254,618.

To all whom it may concern:

Be it known that I, ALFRED J. HENDERSON, a citizen of the United States, residing at Dallas, in the county of Dallas and State of Texas, have invented a new and useful Puzzle, of which the following is a specification.

This invention relates to a puzzle, one of its objects being to provide a phrase which 10 spells the same words beginning at either end of the phrase, and to so arrange the letters of the words that by following certain lines across a surface, the phrase can be spelled beginning at any point on the 15 margin of the surface and continuing to any selected point on the margin. A certain amount of skill is required in order to spell 20 out the words of the phrase so as to bring the user to the selected marginal point and the use of the device in this manner enables it to be employed with considerable pleasure, as a puzzle.

With the foregoing and other objects in view which will appear as the description 25 proceeds, the invention consists of certain novel features of construction and combinations of parts which will be hereinafter more fully described and pointed out in the claims, it being understood that various changes may 30 be made in the arrangement of the parts without departing from the spirit or sacrificing any of the advantages of the invention as set forth in the claims.

In the accompanying drawings the preferred form of the invention has been shown.

In said drawings

Figure 1 is a plan view of the puzzle.

Fig. 2 is an edge view thereof.

Referring to the figures by characters of 40 reference 1 designates a thin board or other structure which can be of any form desired and on the margin of which are spaces in which appear the letter "A" and extending across one or both faces of the structure 45 at right angles to each other, are parallel columns 2 forming, at their points of intersection, square spaces containing the remaining letters of the phrase to be spelled.

This phrase is "Able was I ere I saw Elba" and, as will be apparent, reads the same 50 when spelled from either end. The letters are arranged inwardly from the margin, the first spaces from the margin in each column containing the letter "B", the second space the letter "L", the third space the letter "E", 55 etc., to the center of the surface where the middle letter "R" of the phrase appears. Obviously the entire phrase can be readily traced along either of the central diagonal columns but by selecting a point of starting 60 at the margin and a point of stopping, it often proved a puzzle to get from one point to the other without using the same letter more than once. For example to begin at the point 3 and stop at the point 4 any of 65 the courses marked by the dotted lines could be followed and by specifying certain letters on the chart that must be used in spelling the phrase, the solution of the puzzle is rendered more difficult.

70 What is claimed is:-

1. A puzzle including a surface on which are provided intersecting columns, there being an arrangement of letters in the spaces formed by the intersecting columns whereby 75 the same phrase will be spelled by following a column or columns from one selected marginal point to any other selected marginal point.

2. A puzzle including a surface on which 80 are provided intersecting columns, there being an arrangement of letters in the spaces formed by the intersection of the columns and on the margin at the ends of the columns whereby the same phrase will be spelled by 85 commencing with any selected letter on the margin and following a certain column or columns to any other selected letter on the margin.

In testimony that I claim the foregoing 90 as my own, I have hereto affixed my signature in the presence of two witnesses.

ALFRED JASPER HENDERSON.
